United States Patent Office

Des. 191,243
Patented Aug. 29, 1961

191,243

AIRPLANE

Clarence L. Johnson, Encino, Calif., assignor to Lockheed Aircraft Corporation, Burbank, Calif.

Filed Mar. 17, 1958, Ser. No. 50,073

Term of patent 14 years

(Cl. D71—1)

FIGURE 1 is a perspective view of an airplane showing my new design;

FIGURE 2 is a front elevational view thereof;

FIGURE 3 is a top plan view thereof; and

FIGURE 4 is a side elevational view thereof.

The essential features of the design reside in the portions shown in full lines.

I claim:

The ornamental design for an airplane, substantially as shown and described.
